(57) **CLAIM**

The ornamental design for a magnetic tool holder in the shape of a wrench, as shown and described.

DESCRIPTION

FIG. 1 is a top perspective view of the magnetic tool holder in the shape of a wrench according to the present design; FIG. 2 is a bottom perspective view of the magnetic tool holder in the shape of a wrench as shown in FIG. 1; FIG. 3 is a top plan view of the magnetic tool holder in the shape of a wrench as shown in FIG. 1; FIG. 4 is a bottom plan view of the magnetic tool holder in the shape of a wrench as shown in FIG. 1; FIG. 5 is a right side view of the magnetic tool holder in the shape of a wrench as shown in FIG. 1; FIG. 6 is a left side view of the magnetic tool holder in the shape of a wrench as shown in FIG. 1; FIG. 7 is a front plan view of the magnetic tool holder in the shape of a wrench as shown in FIG. 1; and, FIG. 8 is a bottom plan view of the magnetic tool holder in the shape of a wrench as shown in FIG. 1. The broken lines shown in the drawing disclosure are for illustrative purposes only and form no part of the claimed design.
